(57) **CLAIM**

We claim an ornamental design for a self-service station with two shelves and a holder, as shown and described.

DESCRIPTION

FIG. 1 is an isometric view of a self-service station with two shelves and a holder in accordance with our invention;

FIG. 2 is a front plan view thereof;

FIG. 3 is a top plan view thereof;

FIG. 4 is a rear plan view thereof;

FIG. 5 is a bottom plan view thereof;

FIG. 6 is a right side plan view thereof; and,

FIG. 7 is a left side plan view thereof.

The broken lines showing is included for the purpose of illustrating environment and forms no part of the claimed design.
